UNITED STATES PATENT OFFICE

WALTER BRUNSTETTER AND JESSE R. BRUNSTETTER, OF METUCHEN, NEW JERSEY

TRANSIT LEVEL

Application filed March 16, 1929. Serial No. 347,493.

The main object of this invention is to provide a leveling beam provided with bubbles which are factory-adjusted, and the beam has means thereon for guarding and protecting the bubbles when the same are not in use. 5

Another object of this invention is to provide a transit level having bubbles which have means for minute adjustment.

10 Still another object of this invention is to provide a transit level, in which a lens system is incorporated, for sighting a target at any desired distance in order to pre-determine a horizontal height parallel to the leveling means at a pre-determined distance.

A further object of this invention is to provide means for adjusting the entire transit level to a plumbing position upon an angular base.

20 The above and other objects will become apparent in the description below, in which characters of reference refer to like-named parts in the drawings.

Referring briefly to the drawings, Figure 25 1 is a longitudinal partly sectioned elevational view of the transit level, showing portions thereof in sections to illustrate the locations of the various members of the transit level.

30 Figure 2 is a full size longitudinal sectional elevational view of the mechanism in the lens system for adjusting the cross wires of the transit level.

Figure 3 is an end elevational view of Figure 2.

35 Figure 4 is a full size view of the horizontal bubble, showing the method of mounting the same.

Figure 5 is a front elevational view of a 40 modified means of adjusting the vertical bubbles as used in an all-metallic structure.

Referring in detail to the drawings, the 45 numeral 10 indicates a level beam rectangular in cross section. Near one end of this beam 10 a pair of adjacently facing bubbles 11 and 12 are mounted. These bubbles 11 and 12 are visible in an aperture 13 and are mounted in bores in which spaced-apart rings 14a are anchored. The space between 50 the rings 14a, which are anchored in the

bore receiving the bubbles 11 and 12, receives a rotatable sleeve 14 retained in any desired rotative position by means which will be further hereinafter described. One end of the bore in which the bubbles 11 and 12 are received, is filled with gypsum or other material and is capped by a plate 16 so that it is permanently sealed and adjusted at the place of manufacture. 55

Midway the length of the beam 10 a longitudinal recess is formed in which rests a bed plate 17. This bed plate 17 partly houses a barrel 18 whose ends are joined to supports 19 and 20. The barrel 18 is provided with a longitudinal opening to make the bubble 22 visible, and has revolvable thereon a guard sleeve 21, which is also provided with an opening, and is knurled throughout its surface. The support 20 has a projecting curved surface 23 on its face, which surface 70 23 seats upon the bed plate 17. To permit adjustment of the bubble unit illustrated in Figure 4, a hole in the support 20 is provided in which is received a threaded cap screw 24 which passes through the tapering opening in the support 20 and threads into an opening in the bed plate 17. The opposite support 19 is provided with a pair of set screws 25 and 26 for locking the adjusted position of the level unit illustrated in Figure 4. The set screw 25 threads into an opening in the support 19 and its lower end rests upon the bed plate 17, while the remaining cap screw 26 passes through a clearance opening in the support 19 and is engaged in the threaded opening formed in the bed plate 17. A clearance hole is formed in the bed plate 17 beneath the sleeve 21. 75

This clearance hole receives a resilient coil spring 27 therein upon which rests a friction ball 28 whose surface is at all times in contact with the knurled periphery of the guard sleeve 21 and frictionally retains this guard sleeve 21 in any desired and adjusted position. The recess in which the bed plate 17 rests is covered by a cap plate 29 through which the bubble unit 22 illustrated in Figure 4 partly projects. 90

A bore enters into the beam 10 from the surface upon which the level unit illustrated 100

in Figure 4 is mounted. This bore receives an eye glass 30, or an eye piece lens, when desired. The eye glass 30 is retained in position by a plate 31. The light rays passing through the eye glass 30 impinge upon the reflecting surface of a prism 32 mounted in a frame 33 one of whose ends rests upon the end of a lens system body tube 34. The body tube 34, intermediate its length, is provided with longitudinal slots 35. Mounted slidably within the body tube 34 is a shiftable tube section 36. One end of the tube section 36 has a magnification lens 37 mounted therein by bezelling into place. The opposite end of the tube section 36 has a ring 38 mounted in place, and this ring 38 is equipped with intersecting cross wires 39 and 40 and is adjustably fitted in this tube section 36 with the aid of set screws 41.

20. The tube section 36 has a pair of diametrically opposite follower dogs 42 mounted upon its outer periphery. These follower dogs 42 are slidable in the slots 35 formed in the body tube 34 and these follower dogs 42 permit focal adjustment of the cross wires 39 of the lens system. One of the surfaces of the follower dogs 42 is provided with helical threaded sections 43 which are engaged by an adjusting collar 44 mounted in a recess 45 formed in the region where the collar 44 is located.

30. Adjacent the vertical bubble units 11 and 12 means are provided for adjusting the leveling surface of the beam 10. The unit 35 adjacent the bubbles 11 and 12 and between the end plate 46 and the bubble 11 comprises a cylinder 47 in which a threaded bore is formed. This cylinder 47 is provided with a cap shoe 48 normally located in a recess 40 formed in the level surface 62 of the beam 10. The cylinder 47 is provided with a longitudinal channel or the like which prevents rotational movement of the cylinder 47. A threaded spindle 49 is rotatably anchored in the beam 10, and the threaded portion of said spindle 49 enters into the threaded bore of the cylinder 47, and when the thumb nut 50, forming part of the spindle cylinder 49, is rotated, the cylinder 47 and cap shoe 48 are shifted to a projecting position or are telescoped into the beam 10.

35. The opposite end of the beam 10 may not use this type of construction, as the lens system passes through this end of the beam 10. Another construction is required and comprises a shoe 51 and a pin 52 which latter is rotatably positioned on the leveling surface 62 of the beam 10. When using a three point support for the beam the shoe 51 is rotated to a position at right angles to the position shown in Figure 1 and the screws are then adjusted by rotating the level so that the one end of the beam may be raised or lowered to plumb said beam arcuately. This plumb-ing is obtained through cooperation of the

shoe 51 and adjusting screws 53 which form one leveling unit and member 47 and shoe 48 which latter two members form the second leveling unit. These two units are adjusted to suit the surface upon which the leveling beam is to be plumbed. The pin 52 permits rotation of the shoe 51 and allows a three-point support for the beam 10 when it is to be levelled upon an inclining or uneven support base. The ends of the shoe 51 are provided with adjusting screws 53 having knurled heads which normally may be rotated into guarded position in recesses 54.

40. The level thus far disclosed has its beam 10 formed of some suitable material, such as wood. In the construction of an all-metallic level, the means of mounting the vertical bubbles 11 and 12 and a different construction for the adjustment of these bubble units 11 and 12 must be resorted to. The bubble units 57 and 58 in an all-metallic level are mounted between the side rails 55 and 56 of the all metallic level. These side rails 55 and 56 are provided with a series of spaced-apart lugs 59 between which the bubble units 57 and 58 are located. Each of the bubble units 57 and 58 has a lug, such as that indicated by the numeral 59, on either side of the member. These lugs 59 are provided with threaded holes in which are engaged the ends of threaded set screws 60 which at one end engage the bubble units 57 and 58 and at the opposite ends enter into the threaded holes in the lugs 59 and may be adjusted through means of the spanner holes 61 formed in the set screws 60, at desirable positions. The end of a hollow or skeleton leveling beam is shown in Figure 5. In this figure, means are shown for plumbing the bubbles upon the levelling beam at the factory. The construction of this bubble unit comprises a threaded stem 60, as previously stated, which engages one end of the bubble units. The opposite ends of these bubble units are securely positioned in stationary location upon a rod which is anchored in lugs similar to the lugs 57. These rods and bubbles cannot be shifted at their lower ends and when adjustment is desired, an escutcheon pin or the like is inserted into the spanner holes 61 and in this manner the upper ends of the bubble units are shifted without disturbing the position of the opposite ends of these bubble units. As small adjustment of one of the ends of the bubble units is all that is necessary, the casings holding these bubble units may be readily flexed a few thousandths of an inch.

45. The uses to which a device of this type may be put are many and quite obvious to the art. For general plumbing purposes of a horizontal plane, the intermediate level unit illustrated in Figure 4 is used in reading the position of the beam 10. When locating a vertical surface, the bubbles 11 or 12 are used, according to the position in which the level

is held. These bubble units 11 and 12 are provided with rotatable guard sleeves, such as those indicated by the numeral 14. When desiring to plumb the beam 10 upon an irregular or inclined surface, the cylinder 47 is projected or actuated by manipulation of the thumb nut 50 surmounting the threaded spindle 49, or by adjustment of the screws 53 which are threadable in the rotatable shoe 51. Manipulation of these two units 50 and 53 will permit an accurate and minute adjustment of the beam 10 to any desired angular position within the limits of the instrument. The lens system of the device is adapted to aid in locating a pre-determined level 15 of the beam 10 at a distance on a target or similar other device from which a reading may be had remote from the beam 10. When desiring to plumb a horizontal surface at a 20 position remote from the beam 10, the beam 10 is first plumbed or leveled and a target is then sighted through the eye glass 30. This eye glass reflects the light rays by means of the prism 33 in a right-angled direction through the intermediate lens 37 and across the focal plane, which latter exists at the intersection of the cross wires 39 and 40. This 25 focal plane may be varied to suit the needs of the user of the device by rotation of the threaded ring 44 through use of which the tube section 36 is shifted longitudinally in the body tube 34 through the medium of the follower dogs 42 engaging the ring 44. The 30 image of the target or whatever other reading means is used may be sighted through the objective lens 46, and the necessary planes for permanently locating this reading may then be made.

The bubble units 57 and 58 illustrated in 40 Figure 5 are adapted to be constructed in the manner shown in Figure 5 when an all-metallic beam is used, and the construction and adjustment of these bubble units 57 and 58 are quite obvious to the art from the 45 illustration.

It is to be noted that certain changes in form and construction may be made without departing from the spirit and scope of the invention.

We claim:

1. In a device of the class described, a beam, a prismatic lens system in said beam adapted to sight a point distant from said beam to align said point with said beam, said beam having a bore therein, an objective lens at one end of said bore, a prism at the opposite end of said bore, means for sighting through said prism and objective lens, a movable variable lens, a tube slidable in said bore carrying said objective lens, a cylinder housed in said bore housing said tube and having slots therein, and means mounted on said tube slidable in said slots for adjusting the position of said variable lens with respect 65 to said prism and objective lens.

2. In a device of the class described, a beam, a prismatic lens system in said beam adapted to sight a point distant from said beam to align said point with said beam, said beam having a bore therein, an objective lens at 70 one end of said bore, a prism at the opposite end of said bore, means for sighting through said prism and objective lens, a movable variable lens, a tube slidable in said bore carrying said objective lens, a cylinder housed 75 in said bore housing said tube and having slots therein, follower dogs mounted on said tube having threaded surfaces thereon, and means engaging said threaded surfaces to shift said tube in said cylinder with respect 80 to said prism and said objective lens.

3. In a device of the class described, a beam, a prismatic lens system in said beam adapted to sight a point distant from said beam to align said point with said beam, said beam 85 having a bore therein, an objective lens at one end of said bore, a prism at the opposite end of said bore, means for sighting through said prism and objective lens, a movable variable lens, a tube slidable in said bore carrying said objective lens, a cylinder housed 90 in said bore housing said tube and having slots therein, follower dogs mounted on said tube having threaded surfaces thereon, a threaded ring engaging said follower dogs, 95 said ring when rotated being adapted to shift said follower dogs and tube longitudinally in said cylinder to adjust the distance between said variable lens and said prism and objective lens.

In testimony whereof we affix our signatures.
